UNITED STATES PATENT OFFICE.

THEODORE C. MUELLER, OF TOPEKA, KANSAS, ASSIGNOR OF ONE-HALF TO WINDOM L. KEMPER, OF TOPEKA, KANSAS.

SEALING DEVICE.

1,385,749.

Specification of Letters Patent. Patented July 26, 1921.

Application filed January 23, 1920. Serial No. 353,468.

To all whom it may concern:

Be it known that I, THEODORE C. MUELLER, a citizen of the United States, residing at Topeka, in the county of Shawnee and State 5 of Kansas, have invented certain new and useful Improvements in Sealing Devices; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to a sealing device, particularly adapted to apply a seal by the action of heat so that a container will be closed against unauthorized inspection.

Heretofore, containers have usually been 20 sealed by the utilization of a certain fusible material, such as wax or the like, but the fusible material had to be melted during its application and the necessity for employing a flame for the purpose is more or less ob- 25 jectionable.

I have provided means whereby the seal 30 may be fused so as to flow over the container to efficiently seal it and without the necessity of employing a flame, such as a lamp, candle or the like.

According to my invention, the seal may 35 be initially placed upon the container or package in wafer form and subjected to the action of an electrically heated apparatus to fuse it, there being enough pressure applied to cause the fused material of which 40 the wafer is formed to flow into the creases and crevices of the container or package so that an efficient application of the seal will be assured.

In the drawings,

Figure I is a perspective view of a sealing device constructed in accordance with my invention.

45 Fig. II is an enlarged cross sectional view through the electric contacts in the circuit for energizing the heating element.

Fig. III is a sectional view through the

seal or wafer to be applied to the package or container.

50 Fig. IV is a vertical cross sectional view through the sealing device, and

Fig. V is a transverse sectional view on the line V—V of Fig. IV, looking in the direction of the arrows.

55 In the preferred embodiment of my invention I have shown a substantially rectangular frame consisting of the sides 1 and 2, the top 3 and bottom or floor 4, the sides being extended slightly below the bottom to provide spacing legs or flanges 5 and 6, coextensive with the depending flange 7 surrounding the central opening 8 so that the bottom or floor 4 will be spaced above the device to be sealed and the flange 7 is of sufficient depth to maintain the flowing material wafer within a confined space so that a neat appearance will be presented when the sealing device is removed.

60 The sides 1 and 2 are provided with elongated slots 9 and 10 in which the guide pins 11 and 12 of the heater-actuating frame operate. The heater-actuating frame is shown as consisting of a substantially inverted, U-shaped member having side bars 13 and 14 65 in which the pins 11 and 12 are respectively connected, and the bars 13 and 14 are connected at their upper ends by a head or cross bar 15, on which is mounted a handle 16 having a central tubular portion 17, into 70 which telescopes a tube 18, rigid on the top 3 of the frame and within the tube 18 is an expansion spring 19, one end of which bears against the upper closed end of the tube 17 so that the normal tendency will be for the 75 yoke-shaped frame to maintain itself in extended position, as shown in Fig. I, so as to retract the heating element 20 away from the floor 4 of the main frame.

80 The heating element is shown as consisting of an inclosing casing fastened to the side bar 13 by a connection 21 and to the insulation blocks 22 and 23 on the member 14 by conducting fastening devices 24 and 25, 85 one of which serves as a positive conductor and the other a negative conductor for the 90

heating element within the casing 20, it being understood that a known type of heater may be contained within the casing 20 to raise the same to the desired temperature for the purpose intended.

The blocks 23 and 24 carrying contacts 26 and 27, which are adapted to move into and out of engagement with the spring contacts 28 and 29 on the side 2 of the main frame 10 and located at opposite sides of the slot 10, as clearly shown in Fig. I, and these contacts are in circuit with a connector 30 adapted to be electrically connected to a suitable source of supply as, for example, a commercial circuit. Therefore, when the contacts 26 and 27 bear against contacts 28 and 29, the filament in the casing 20 will be energized so as to generate heat and communicate the heat to the casing so that the sealing wafer 31 20 may be caused to fuse and adhere to the container or package to which it is to be applied.

I prefer to construct the seal of substantially wafer form with gradually decreasing cross sectional area toward the center and I have, therefore, shown a wafer in Fig. III as having a relatively flat top 32 and a concave nether face 33 so that when the wafer is placed in the opening 8, the peripheral edge 34 will bear against the container or package with the central portion spaced therefrom. The operator may then press upon the handle 16 to force the fuser or heater casing 20 against the top side 32 of the wafer with a gentle pressure and as the member 20 moves into wafer-engaging position, the circuit will be closed, causing a sufficient rise in temperature of member 20 to fuse the wax and cause it to flow over the 40 surface of the container or package. The original contour of the wafer will be maintained by the flange 7 since the wax will not flow past the edge of the opening and after the wafer has been fused, the operator releases the pressure on handle 16, permitting the expansion spring 19 to raise the yoke-shaped member and with it, the heater, whereupon the circuit is broken. The wafer may be permitted to cool so that when the 50 sealing device is removed, a seal of neat appearance will have been applied to the container or package.

The operation of sealing requires the expenditure of a minimum amount of time and 55 a number of successive operations may be performed in an expeditious manner by first introducing a wafer in the opening 8, pressing upon the handle 16, releasing the handle, removing the sealing device, and applying it to the next container or package with an additional wafer in the opening 8.

From the foregoing it will be apparent that the device is of simple construction, easily operated, and that an efficient and neat 65 seal may be applied to a container or pack-

age without the necessity of employing a flame to melt the fusible material of which the wafer is made.

For the purpose of illustration, I have shown the opening 8 as round but it is obvious that it may have any contour and that the member 20 may have a die on its under side so that certain indicia may be impressed on the face 32 of the wafer at the same time that it is being fused on the container or 75 package.

What I claim and desire to secure by Letters-Patent is:

1. In a sealing device, a frame having an opening to receive a wafer of fusible material, and a heater having movement with respect to said frame, the heater being receivable within the opening. 80
2. In a sealing device, a holder for a fusible seal, and a seal fuser and presser co-operating therewith to bodily apply the seal to the article to which it is to be attached. 85
3. In a sealing device, a member having an opening for a fusible wafer, and a heatable pressure device for applying heat and pressure to the wafer while in the opening. 90
4. In a sealing device, a member for receiving a fusible wafer having an opening into which a wafer may be placed, a heatable pressure device, the cross sectional area 95 of which is co-extensive with said opening, and means for moving the pressure device into wafer-pressing position.
5. In a sealing device, a rectangular frame having a wafer-receiving opening, a supplemental, yoke-shaped frame, the side bars of which pass through slots in the top of the rectangular frame, and a heatable presser head carried by the side bars of the yoke-shaped frame and movable into and out of 100 said opening.
6. In a sealing device, a frame having a fusible-wafer receiving means, and a wafer pressing and fusing element co-operating with said frame and movable into contact 110 with a wafer carried thereby to press against and bodily fuse the entire wafer.
7. In a sealing device, a frame having a framing opening for sealing material, the contour of which determines the contour of 115 the applied seal, a presser head carried by the frame having movement into and out of the opening, the cross sectional area of the presser head being co-extensive with that of the opening, and means for heating the 120 head when it moves into pressing position.
8. In a sealing device, a frame having a fusible-wafer receiving opening, a supplemental frame slidable with respect to the first named frame, an electrical heating element carried by the supplemental frame and having a face co-extensive with the opening, means for sliding the frame to bring the heating element into contact with a wafer in the opening, and contacts between the two 125 130

frames and mounted to complete a circuit when the supplemental frame is moved in one direction and to break the circuit when the supplemental frame is moved in the opposite direction.

9. In a sealing device, a vertical, rectangular frame having an opening in the floor thereof to receive a wafer of fusible material, a secondary frame slidable with respect

to the first named frame, an electrically energized heater carried by the supplemental frame and having contacts to engage the contacts on the first named frame, said heater being of such form as to be receivable within the wafer-receiving opening.

In testimony whereof I affix my signature.

THEODORE C. MUELLER.
